[57] CLAIM

The ornamental design for a tortilla warmer, as shown and described.

DESCRIPTION

FIG. 1 is an exploded top, front perspective view of a tortilla warmer showing my new design;

FIG. 2 is a top plan view thereof;

FIG. 3 is a right side elevational view thereof; the side opposite is a mirror image thereof;

FIG. 4 is a bottom plan view thereof; and

FIG. 5 is an exploded sectional view thereof taken on line 5—5 of FIG. 2.

FIG. 1
